[57] CLAIM

The ornamental design for a combined seat and detachable tray for a child, substantially as shown and described.

DESCRIPTION

FIG. 1 is a perspective view showing my design for a combined seat and detachable tray for a child; FIG. 2 is a perspective view similar to FIG. 1, but showing the article wherein the detachable tray is removed for convenience of illustration; FIG. 3 is a side elevational view thereof, the opposite side being a mirror image thereof; FIG. 4 is a top plan view thereof; FIG. 5 is a bottom plan view thereof; FIG. 6 is a front elevational view thereof; and FIG. 7 is a rear elevational view thereof.

FIG. 5
